UNITED STATES PATENT OFFICE.

WYVIL HARTLEY LAKE, OF STOKE-UPON-TRENT, ENGLAND.

GAS-REVERSING VALVE.

1,424,832.

Specification of Letters Patent. Patented Aug. 8, 1922.

Application filed August 16, 1921. Serial No. 492,854.

(GRANTED UNDER THE PROVISIONS OF THE ACT OF MARCH 3, 1921, 41 STAT. L., 1313.)

To all whom it may concern:

Be it known that I, WYVIL HARTLEY LAKE, a subject of the King of Great Britain and Ireland, residing at Stoke-upon-Trent, in the 5 county of Stafford, England, have invented Improvements in or Relating to Gas-Reversing Valves (for which I have filed application in Great Britain dated March 9th, 1920, No. 151,541), of which the following

10 is a specification.

This invention relates to gas reversing valves of the kind in which a so-called "tub" or hood, liquid sealed at the perimeter, possesses a partition adapted to occupy different 15 liquid sealed positions between multiple gas ways, and to permit of the gas circulation being altered by raising, turning and lowering movements of the hood the means for effecting which form no part of the present 20 invention.

According to the present invention it is arranged that the hood space comprises two separate arched metal casings or framings adapted to be mounted upon a skeleton plate 25 carrier from which depend the outer apron and intermediate partition requisite for sealing purposes, the said carrier serving also to firmly support a refractory lining which, by reason of the shape of the casings or 30 framings may be constituted of fire bricks of the shapes in common use. The partition, which dips into the liquid seal, is formed as a trough to contain liquid so that it is not liable to warp if exposed unduly to 35 hot gases as for example when it is raised to break the liquid seal.

Further when it may be desired that the gases and sealing liquid should not be exposed one to the other more than can be 40 avoided the luting regions for the time being unoccupied by the partition of the hood may be covered or protected by members similarly supported by or from the skeleton carrier referred to, it being preferred that such 45 members should themselves be internally liquid cooled.

Whilst the invention can be variously carried into effect it will suffice to describe one constructional example with the aid of the 50 accompanying drawings in which Fig. 1 is a sectional elevation and Fig. 2 a plan with parts removed, of a valve suitable for use with ingot soaking pits for example, Fig. 3 is a part sectional view of a detail. Fig. 4 55 is a sectional elevation illustrating a modifi-

cation, and Figs. 5 and 6 are views illustrating alternative forms which members in Fig. 4 may, in cross section, assume.

Referring first to Figs. 1, 2, 3, and 4, *a* 60 are two metal casings which, at the centre are of the cross sectional shape shown in Fig. 1, the casing edges *d*, being straight from end to end.

The casings *a* are each shown as attached to the upstanding flange of an internal angle iron *e* borne by a ring-like plate *f* having cross members *g* and reinforced by outer angle iron rings *h*, *i*. The angle irons *e*, as will be seen, provide a good support for a brickwork lining *j* to the casings *a*. The 70 water pan *k* is of ordinary construction and receives the apron *m* as usual, the partition between the casings *a* which depends into either the water channel *n* or *o* however being made as a trough *p* suspended from beneath the members *g* and adapted to contain water in a manner broadly well known. To determine the level of water therein, overflow means may be provided, such as an 75 upstanding pipe arranged centrally of the trough, at one or other or each end thereof or at several of these positions, Fig. 3 illustrating an end overflow pipe *r* extending from the trough *p* through the apron *m* and discharging into the circular sealing channel 80 of the pan *k* the overflow from which is shown at *s*.

In cases where it is desired to avoid the exposure or free exposure of the surface of water in the sealing pan to the action of the gases being controlled, arms *t* may, as shown in Fig. 4, be employed to cover the passages *n* or *o* in the pan *k* when the partition *p* occupies the passages *o* or *n* respectively. These arms *t* may be of a section 95 such as shown in Fig. 5 corresponding to the arm in the right hand half of Fig. 4, and communicate with the trough *p* so as to become filled with water, being wide enough to rest upon the walls of the passages *n* or *o* if desired which may be effected by lowering the hood the necessary extent. Or the arms may be of a section such as shown in Fig. 6 corresponding to the arm in the left hand half of Fig. 4, and carry a covering *u* of 100 firebrick or like material, adapted to engage the channel walls if the hood is sufficiently lowered.

What I claim is:—

1. In a gas reversing valve of the kind 110

- referred to, a vertically movable hood comprising two separate arched casings of metal, a trough uniting adjacent edges of such casings, said trough having closed ends, and a liquid seal which the trough aforesaid enters when the hood is in its lowermost position said trough, when elevated as well as when lowered, containing liquid sufficient to prevent warping.
- 10 2. In a gas reversing valve of the kind referred to, a vertically movable hood comprising two separate arched casings of metal, a trough uniting adjacent edges of such casings, said trough having closed ends, a liquid seal which the trough aforesaid enters when the hood is in its lowermost position and overflow means whereby the level of liquid supplied to said trough is determined.
- 15 3. In a gas reversing valve of the kind referred to, embodying multiple gas ways formed in a water pan having intersecting luting channels, a vertically movable hood comprising two separate arched casings of metal, a trough having closed ends uniting adjacent edges of such casings and adapted to enter any one of said intersecting channels, and hollow arms extending laterally from the trough adapted to be supplied with liquid therefrom and covering the remaining luting channels that are for the time being beneath the casings.
- 20 4. In a gas reversing valve of the kind referred to, embodying multiple gas ways formed in a water pan having intersecting luting channels, a vertically movable hood comprising two separate arched casings of metal, a trough having closed ends uniting adjacent edges of such casings and adapted to enter any one of said intersecting channels, hollow arms extending laterally from the trough adapted to be supplied with liquid therefrom and covering the remaining luting channels that are for the time being beneath the casings.
- 25 5. In a gas reversing valve of the kind referred to, embodying multiple gas ways formed in a water pan having intersecting luting channels, a vertically movable hood comprising two separate arched casings of metal, a trough having closed ends uniting adjacent edges of such casings and adapted to enter any one of said intersecting channels, hollow arms extending laterally from the trough adapted to be supplied with liquid therefrom and covering the remaining luting channels that are for the time being beneath the casings, and a protective covering of refractory material surmounting said lateral members.
- 30 6. In a gas reversing valve of the kind referred to, embodying multiple gas ways formed in a water pan having intersecting luting channels, a vertically movable hood comprising two separate arched casings of metal, a trough having closed ends uniting adjacent edges of such casings and adapted to enter any one of said intersecting channels, hollow arms extending laterally from the trough adapted to be supplied with liquid therefrom and covering the remaining luting channels that are for the time being beneath the casings, and a protective covering of refractory material surmounting said lateral members, said protective covering being adapted to rest upon the edges of the luting regions when the hood is in its lowermost position.

Signed at Stoke-upon-Trent, England,
this twenty-ninth day of July, 1921.

WYVIL HARTLEY LAKE.
